(57) **CLAIM**

What is claimed is an ornamental design for a visor, as shown and described herein.

DESCRIPTION

FIG. 1 illustrates a top perspective view of a visor; FIG. 2 illustrates a front view thereof;

FIG. 3 illustrates a rear view thereof;

FIG. 4 illustrates a left-side view thereof;

FIG. 5 illustrates a right-side view thereof;

FIG. 6 illustrates a top view thereof; and,

FIG. 7 illustrates a bottom view thereof.

The broken lines within the bounds of the visor depict stitching that forms no part of the claimed design.
